UNITED STATES PATENT OFFICE.

CHARLES W. IRION, OF RED CLIFF, COLORADO.

GUN-SIGHT.

1,387,987.

Specification of Letters Patent. Patented Aug. 16, 1921.

Application filed November 8, 1919. Serial No. 336,608.

To all whom it may concern:

Be it known that I, CHARLES W. IRION, a citizen of the United States, residing at Red Cliff, in the county of Eagle and State 5 of Colorado, have invented certain new and useful Improvements in Gun-Sights; and I do hereby declare the following to be a full, clear, and exact description of the invention, such as will enable others skilled in 10 the art to which it appertains to make and use the same.

This invention relates to gun sights of the cross bar or wire type, and the primary object of the invention is to provide an improved means for holding and fastening the wires in position so that the same may be 15 replaced when worn or broken.

Another object of the invention is to provide an improved means for holding the 20 wires of a gun sight of the cross bar or wire type in such a manner that the same may be readily and quickly removed or replaced when broken or worn, without necessitating the use of any tools or fastening elements.

25 A still further object of the invention is to provide an improved gun sight of the above character, which is durable and efficient in use, one that is simple and easy to manufacture and one which can be placed 30 upon the market at a reasonable cost.

With these and other objects in view, the invention consists in the novel construction, arrangement and formation of parts, as will be hereinafter more specifically described, 35 claimed and illustrated in the accompanying drawings, forming a part thereof in which:

Figure 1 is a front elevation of the improved gun sight,

Fig. 2 is a central longitudinal section 40 through the same, and

Fig. 3 is a detail perspective view of the inner wire carrying member.

Referring to the drawings in detail, wherein similar reference characters designate corresponding parts throughout the several views, the numeral 1 generally indicates the improved gun sight which includes an outer ring 2 having the base 3 integrally or rigidly connected thereto. The base 3

50 forms means whereby the ring 2 may be secured to a fire-arm (not shown). The ring 2 has slidably mounted therein the inner member or sleeve 4, which is adapted to snugly fit in the ring and be held in en-

gagement with the same against accidental 55 displacement by frictional contact.

The inner sleeve 4 is provided at four equidistant spaced points with inwardly extending slots 5, which terminate at a point substantially half-way between the terminals 60 of the sleeve.

The slots 5 are formed of such width as to snugly receive the sight wires or rods 6, which cross each other at the axis of the sleeve 4. The terminals of the wires are inserted or slid in the slots 5 and the projecting ends are bent inwardly at right angles, as at 7, in close engagement with the outer surface of the sleeve. After the wires have been placed in position, the sleeve 4 is 70 then slid in the outer ring 2 and the terminals of the wires coming in frictional contact with the ring effectively hold the wires and sleeve against accidental displacement. This forms an efficient means for holding the 75 wires in position and permits the same to be readily and quickly removed, when desired without the use of any tools.

In practice, I have found that the form of my invention, illustrated in the accompanying drawing and referred to in the above description, as the preferred embodiment, is the most efficient and practical; yet realizing the conditions concurrent with the adoption of my device will necessarily vary, 80 I desire to emphasize the fact that various minor changes in details of construction, proportion and arrangement of parts may be resorted to, when required without sacrificing any of the advantages of my invention as set forth.

What I claim as new is:—

1. A gun sight having a body member, removable crossed sight wires, a sleeve having retaining means serving as gages to 95 position said wires, said wires being positioned in said means and extending beyond the sleeve, and said sleeve being slidable into the body so that the extended portions of the wires will frictionally engage the interior 100 of the body to fasten the wires in place and the sleeve and body against accidental relative movement.

2. A gun sight comprising an annular body, a sleeve slidably mounted in said body, 105 said sleeve having inwardly extending slots therein, crossed sight wires, said slots serving as gages for said wires, said wires

being removably positioned in said slots and
having their terminals overlying the outer
surface of said sleeve, said angular termi-
nals engaging the inner surface of the annu-
lar body when the sleeve is positioned there-
in to frictionally secure the wires in place
and the body and sleeve together.

In testimony whereof I affix my signature
in presence of two witnesses.

CHARLES W. IRION.

Witnesses:

N. J. DURROW,
RUTH TAGUE.
